United States Patent Office

Des. 211,567
Patented July 2, 1968

211,567

HANDLE FOR TROWELS OR THE LIKE

Fred W. Tims, Jr., Strafford, Conn., assignor to The Camson Manufacturing Company, West Haven, Conn., a corporation of Connecticut

Filed Sept. 25, 1967, Ser. No. 8,710

Term of patent 14 years

(Cl. D10—8)

FIG. 1.

FIG. 2.

FIG. 3.

FIG. 1 is a perspective view of a handle for trowels or the like, showing my new design;

FIG. 2 is an end elevation thereof; and

FIG. 3 is a side elevation thereof.

I claim:

The ornamental design for a handle for trowels or the like, substantially as shown.
